UNITED STATES PATENT OFFICE.

CHARLES A. KINNEY, OF MERIDEN, CONNECTICUT, ASSIGNOR TO EDW. MILLER & CO., OF SAME PLACE.

WICK-TUBE.

SPECIFICATION forming part of Letters Patent No. 257,021, dated April 25, 1882.

Application filed March 17, 1882. (No model.)

To all whom it may concern:

Be it known that I, CHARLES A. KINNEY, of Meriden, in the county of New Haven and State of Connecticut, have invented new Improvements in Wick-Tubes; and I do hereby declare the following, when taken in connection with accompanying drawings and the letters of reference marked thereon, to be a full, clear, and exact description of the same, and which said drawings constitute part of this specification, and represent, in—

Figure 1, a sectional side view; Fig. 2, an edge view; Fig. 3, a top view, illustrating the method of making the tongues *a b*; Fig. 4, a perspective view of the cap from the under side.

This invention relates to an improvement in the construction of wick-tubes, whereby the use of solder is avoided; and it consists in upsetting the edges of the tube above and below a projection in the cap through which the tube is passed, with a tongue struck from the cap to extend vertically upon the sides of the tube, as more fully hereinafter described.

A represents the usual cap, fitted to be screwed into the collar in the usual manner; *B*, the wick-tube, also of usual form. In making the cap, instead of cutting the slot for the tube by removing the metal entirely, as by the usual construction, I cut tongues *a b* by separating the metal on one side, beginning at 1 and extending around the end to the point 2 on the opposite side, and the other, *b*, cutting from the point 3 on one side around the end and to the point 4 on the opposite side, leaving the side opposite on each uncult. These tongues are turned one to the right, the other to the

left, as seen in Fig. 4, opening the slot *d* through the bottom of the cap corresponding to the shape of the tube, this differing from the usual construction in that the tongues *a b* are produced.

The tube has a projection, *e*, formed in its edge, so as to extend over the end of the slot *d* and form a shoulder, so that the tube will rest thereon. Then, after the tube has been inserted into its slot, I form upon the opposite side a corresponding shoulder, *f*, close up against the under side of the bottom of the cap, as seen in Fig. 1. These prevent vertical movement of the tube. The tongues *a b* lying close against the side of the tube, as seen in Fig. 2, hold it against transverse movement. Hence the tube is firmly secured, and without the application of solder.

The projections *ef* are formed in the usual manner for making these projections by a punch-like operation from the inside outward, or they may be otherwise formed, it only being essential to this invention that the tube shall be interlocked with the cap to prevent vertical movement of the tube.

I claim—

The wick-tube cap *A*, constructed with the tongues *a b*, extending vertically one on each side the slot in the cap, combined with the tube *B*, introduced into the slot between the said tongues and interlocked with the cap, substantially as described.

CHAS. A. KINNEY.
